LOCOMOTIVE STRUCTURE

Julius J. Zach, Moores, Pa., assignor to General
Steel Castings Corporation, Granite City, Ill.,
a Corporation of Delaware

Application September 17, 1931
Serial No. 563,274

18 Claims. (Cl. 105—44)

The invention relates to railway rolling stock and consists in a novel locomotive underframe structure and more particularly in the main steam cylinder, saddle, supply pipe, and adjacent underframe members of a front unit of a mallet type of compound locomotive although some of the features described and claimed herein are not limited to this particular application.

Previous cylinder structures for front units of this type of locomotive have usually been made in two sections which are bolted together on a vertical and longitudinally extending plane at the center of the locomotive and are mounted on the locomotive frame. The steam from the H. P. cylinders of the rear unit is carried through a receiver pipe extending longitudinally along the center of the front unit and the front end of this pipe is connected to a Y-pipe, the branches of which are connected to inlet openings in the rear wall of each cylinder section for passageways leading to the steam chests, as illustrated in Locomotive Cyclopedias of 1925, page 541.

Other previous structures have been made consisting of a center section which is secured to the locomotive frames and separate cylinders bolted to the center section on each side. The receiver pipe is connected to a separate longitudinally and downwardly extending pipe section at the center of the locomotive, which section in turn is connected to an inlet opening in the rear wall of the above mentioned center section, for a longitudinally extending passageway having two branches opening in the top of the center section. Two separate elbow pipe sections are connected to the branches at the top and extend transversely in opposite directions from each other and connect with corresponding steam chests on each side, all of which is shown in Locomotive Dictionary of 1916, fig. 588, page 366.

The main objects of the invention are to reduce the amount of fitting and machining previously required for similar equipment, to form a rigid structure having a maximum strength for a minimum weight of material, to avoid unnecessary joints in steam passageways and thereby eliminate leakage in the saddle and reduce maintenance expense, and to otherwise simplify the structure involved. This is accomplished by forming both of the cylinders and corresponding steam chests, the steam passageways and the receiver pipe connections integrally with each other, thereby eliminating the flanges and joints of the previous constructions, and also eliminating the usual Y-pipe at the rear of cylinder castings in one of the previous types of construction.

and the separate pipe sections between the receiver pipe and the steam chests of the other above mentioned previous construction.

Another object is to locate the steam passageways within the cylinder structure where the temperature and pressure of the steam will be better maintained.

Other detail objects will appear from the following description taken in connection with the accompanying drawings in which—

Figure 1 is, in part, a top view of the cylinder saddle and adjacent underframe portion of a locomotive embodying the invention and, in part, is a horizontal section taken on the line 1—1 of Figure 2.

Figure 2 is a vertical transverse section taken on the line 2—2 of Figure 1.

Figure 3 is a vertical longitudinal section taken on the line 3—3 of Figure 1.

Figures 4 and 5 are vertical longitudinal sections taken on the lines 4—4 and 5—5, respectively, of Figure 2.

A portion of the main frame of the locomotive is illustrated as being of box section and having side walls 1, a top wall 2, a bottom wall 3, and intermediate vertical walls 4. Preferably, this underframe is in the form of a one piece casting although this structure is not essential to the invention.

The main steam cylinders 5 are formed integrally with the underframe, each side wall 1 merging with the inner portion 6 of the corresponding cylinder and the top and bottom walls 2 and 3 having lateral extensions 7 and 8 also merging with the cylinder walls. Vertical transverse webs 9 and 10 and suitable reinforcing ribs 11 form part of the body portion of the saddle structure between the cylinders.

A steam supply pipe 12 is located within the box section main frame and extends into the saddle, branching between walls 9 and 10 as indicated at 13 and 14 to lead the steam to the chest 15 which will mount the usual housing (not shown) for the slide valves whereby the distribution of the steam to the cylinders 5 is controlled.

Intermediate each branch 13 and 14 is an exhaust steam passageway 16 leading from the steam chest downwardly and then upwardly above the forward portion of supply pipe 12 and merging with the exhaust steam passageway from the opposite cylinder as indicated at 17 to discharge exhaust steam through the exhaust nozzle (not shown) into the smoke stack. By depressing the passageway as shown, the

110

vertical path of the discharge blast is lengthened and consequently the force of the draft is increased.

The rear portion of supply pipe 12 includes as an integral part thereof the outer packing box 18 of a slip joint for the separately formed conduit (not shown) extending to the rear unit of the locomotive. As best shown in Figure 3, member 18 is integral with the transverse web 19 whereby the inner end of the supply pipe 12 is supported.

By forming all of the parts illustrated in a single casting, steam passageways 13, 14, and 16 form structural members extending across the frame and contribute to the support of the main steam cylinders and steam chests located at the sides of the frame. Also this structure eliminates the usual jointed connection between the cylinders and the saddle and between the two halves of the saddle with the resulting requirements of frequent inspection and tightening of the holding bolts. The structure also eliminates the provision of the usual Y pipe at the rear of the saddle for connection with the supply conduit from the rear unit.

The pipe 12 could readily terminate in a single passageway for a piston valve chamber instead of the divided passageway for the steam chests shown.

Various other changes in the form and details of the structure may be made without departing from the spirit thereof and I contemplate the exclusive use of all such modifications as come within the scope of the appended claims.

What is claimed is:

1. In combination, a locomotive main frame member, steam control chambers at the sides thereof, transverse vertical webs intermediate the ends of said member and bracing said chambers, and a steam supply pipe extending along said member and terminating in branches extending between said webs to said chambers, all of said parts constituting an integral structure.

2. In combination, a locomotive main frame member, main steam cylinders at the sides thereof, transverse vertical webs intermediate the ends of said members and bracing said cylinders, and a steam supply pipe extending along said member terminating in branches extending between said webs to points above said cylinders, all of said parts constituting an integral structure.

3. An integral locomotive structure comprising spaced steam control chambers and a transversely extending member connecting said chambers and having front and rear vertical walls, the structure including a longitudinally extending steam supply passageway located between said chambers and having branches extending transversely within said member to said chambers, said walls merging with said branches and bracing the same.

4. An integral locomotive structure comprising spaced main steam cylinders, a connecting box shaped member, and steam control chambers above said cylinders, the structure including a steam supply passageway within said member, said passageway having branches extending within said member to said chambers.

5. A locomotive structure comprising a box shaped body member, the top and bottom walls of said member projecting beyond the sides thereof, main steam cylinders having side wall portions integral with said top and bottom walls,

and a steam supply pipe enclosed by said body member with diverging branches integral with the walls of said member and said cylinders.

6. An integral locomotive structure comprising spaced main steam cylinders and a connecting member and steam control chambers above said cylinders, the structure including a longitudinally extending steam supply passageway, at least a portion of which is located within said member, said passageway having spaced branches each extending to the end portions of a corresponding steam control chamber, the structure also including an exhaust steam passageway extending transversely inwardly from said chamber and located between said branches. 80 85 90 95

7. In a locomotive structure, main steam cylinders, a longitudinal body member having a depressed portion alongside of said cylinders, steam control chambers above said cylinders, exhaust steam passageways leading inwardly and downwardly from said depressed portion to the interior of said member and then turning upwardly to form an exhaust nozzle mounting adjacent to the level of the bottom of said chambers, and a steam supply passage within said body member and depressed therewith and having transversely extending upwardly inclined outlets merging with said chambers. 95 100

8. An integral locomotive structure comprising spaced main steam cylinders and a connecting member and steam control chambers above said cylinders, the top of the intermediate portion of the connecting member being located at a lower level than the upper portion of said control chambers, the structure including a longitudinally extending steam supply passageway located within said member, said supply passageway having branches extending transversely and upwardly within said member to said chambers, and exhaust steam passageways extending inwardly and downwardly from said chambers and then turning upwardly so as to direct the steam towards the exhaust nozzle. 105 110 115

9. In a locomotive saddle structure, a main body member, a steam supply pipe enclosed therein and extending longitudinally thereof, spaced outlet passageways extending transversely of said pipe, the adjacent walls of said passageways forming portions of the walls of an exhaust steam passageway between said outlet 120 125 130 135 passageways.

10. A locomotive structure comprising spaced steam cylinders and a connecting member, said structure including a steam supply passageway enclosed in said member and extending longitudinally of the locomotive and having spaced outlet passageways extending transversely of said passageway, the adjacent walls of said passageways forming portions of the walls of an exhaust steam passageway between said outlet 130 135 140 145 passageways.

11. In a locomotive saddle structure, a main frame member, a steam supply chamber, an exhaust steam passageway extending inwardly from said chamber through said member, and a steam supply pipe extending longitudinally of said member and beneath said exhaust steam passageway and then branching transversely to said chamber. 140

12. An integral locomotive structure comprising spaced main steam cylinders and a connecting member and steam control chambers above said cylinders, said structure including a steam supply passageway having a portion adapted to be connected to the forward end of a receiver 145 150

- 5 pipe, said portion being spaced rearwardly of said structure and said passageway extending longitudinally and downwardly through said member and within the latter and having branches within said member extending transversely and upwardly in opposite directions and connecting with said steam chambers.
- 10 13. In combination, a locomotive saddle structure including front and rear transverse walls, a steam supply pipe extending longitudinally of the locomotive through said rear wall and terminating in a slip joint member at a point spaced rearwardly of said rear wall, said pipe being integral with the remainder of the saddle structure.
- 15 14. In a locomotive saddle structure, front and rear walls, a steam supply pipe extending longitudinally of the locomotive into the space between said walls and having transversely extending branches located between said walls and extending upwardly and outwardly from the body of the supply pipe, and transverse vertical ribs extending across said saddle beneath said supply pipe and branches.
- 20 15. A box-shaped locomotive main frame member including a plurality of transverse vertical webs intermediate the ends thereof and a steam supply pipe enclosed in said member and carried by said webs.
- 25 16. A locomotive cylinder saddle integral structure including locomotive underframe members, main steam cylinders, and a supply steam passageway enclosed by said members and having lateral branches merging with said members and projecting beyond the latter to merge with portions of said cylinders to assist in the support thereof.
- 30 17. A locomotive saddle construction comprising in an integral casting a main frame member, main steam cylinders outside thereof, supply steam passageways and exhaust steam passageways extending from the inside of said member to the outside thereof and forming transverse members of the saddle supporting and bracing said main steam cylinders.
- 35 18. A locomotive saddle construction comprising in an integral casting a main frame member, supply steam passageways and exhaust steam passageways extending from the inside of said member to the outside thereof and forming transverse members of the saddle to support and brace main steam cylinders.
